UNITED STATES PATENT OFFICE.

WILLARD C. MARKS, OF ETNA, PENNSYLVANIA, ASSIGNOR TO SPANG, CHALFANT & CO., INCORPORATED, A CORPORATION OF PENNSYLVANIA.

DIE-HEAD.

1,352,823.

Specification of Letters Patent. Patented Sept. 14, 1920.

Application filed October 1, 1919. Serial No. 327,753.

To all whom it may concern:

Be it known that I, WILLARD C. MARKS, a citizen of the United States, and a resident of Etna, in the county of Allegheny and 5 State of Pennsylvania, have invented a new and useful Improvement in Die-Heads; and I do hereby declare the following to be a full, clear, and exact description thereof.

My invention relates to die-heads or holders, and has special reference to such heads for holding threading dies for use in the manufacture of pipes or tubes.

The object of my invention is to provide a cheap, simple and efficient die-head, which 15 will provide for the quick opening and closing of the same, will give freedom from wear and give additional strength to its operating parts, will enable the holding of the die in a more rigid position during the operation 20 of threading, and will give increased production, both in quality and quantity, as well as speed in operation and maintenance of definite size of threads until changed by will of operator.

25 A still further object of the invention is to provide a locking means for the die-head for holding the die in its proper and rigid position when the die is in operative position, and which is separate from the means 30 for opening and closing the die-head.

To these ends my invention consists, generally stated, in the novel arrangement, construction and combination of parts, as hereinafter more specifically set forth and described and particularly pointed out in the 35 claims.

To enable others skilled in the art to which my invention appertains to construct and use my improved die-head, I will describe the 40 same more fully, referring to the accompanying sheet of drawings, in which—

Figure 1 is a side elevation of my improved die-head in its closed position;

Fig. 2 is a sectional view on the line 2—2 45 Fig. 1, looking in the direction of the arrows and showing the threading die in position; and

Fig. 3 is a side view, partly in section, of the die-head in its opened position.

50 Like symbols of reference herein indicate like parts in each of the figures of the drawings.

As illustrated in the drawings my improved die-head is shown at A and is formed 55 of two halves or upper and lower yokes 1

and 2, having the front and rear extensions 3 on each of the same and the semi-circular openings 4 in each of said sections intermediate of said extensions for the reception of the die 5 therein. The two yokes 1 and 2 60 of the head A fit within a base or support α which is mounted in the usual head of a threading machine (not shown) and such yokes are connected together at the rear ends of the rear extensions 3 by means of the bolts 65 5 and 5' passing through the same and head α , the outer bolts 5 being mounted in slotted holes 6 in said extensions and head α and a plate 7 fitting over said extensions to permit the opening and closing movements of such 70 yokes, the bolts 5 acting as pivotal points in such movements.

Between the front extensions 3 of the yokes 1 and 2 is the rocking lever 8, which is journaled on a pin 9 secured in the base plate α 75 and is provided with a slotted portion 10 in each of its ends. An L-shaped lever 11 is pivoted on the pin 12, at the end of its short arm in each of said slotted portions 10, and the longer arm of said levers 11 is pivoted at 80 its end, by the pin 13 within a recessed portion 14 in the inner face of each of the front extensions 3 on the yokes 1 and 2. An operating lever 15 is mounted on the pins 9 and 12 for moving the levers 8 and 11 in the 85 opening and closing of the yokes 1 and 2.

Between the front extensions 3 of the yokes 1 and 2 and in the rear of the levers 8 and 11 is a block 16, which is secured to the base plate α by a threaded portion 16' and secured 90 to said block by the screw-bolts 17 is a plate 18 for overlapping the side faces of said extensions to hold the yokes in proper alignment with each other.

Extending through the end of the extension 3 on the upper yoke 1 is the screw-bolt 19, the threaded portion 20 of which engages with said extension, and such bolt is provided with a head 21 at its outer end, while its inner end is adapted to engage with a block 100 22 in the inner face of the lower yoke 2 for permitting the adjustment of such yokes in changing the size of the threads upon the article being threaded.

Passing through a hole 23 in the end of the extension 3 in the upper yoke 1 is the locking bar 24, which is provided with a threaded portion 25 at its upper end, upon which the jam nuts 26 engage beyond the outer face of said yoke, and such hole is enlarged at its 110

- upper portion, as at 23' and is outwardly tapered at its lower portion to permit such bar to swing outward and inward in yoke end. A dowel pin 27 passes through the locking 5 bar 24 for engaging with the inner face of the upper yoke 1, which pin combined with the jam nuts 26 engaging with the outer face of said yoke will hold the bar in position, yet allow it to be moved inward and outward 10 in its locking and unlocking positions, and also permit the adjustment of such bar for operation. The inner end of the bar 24 is provided with a shoulder 28 on the inner face of the same for fitting under the outer face 15 of the yoke 2 when in locking position, and a handle 29 extends out from the outer face of such end for the easy handling of such locking bar in its locking and unlocking movements.
- 20 The use and operation of my improved die-head A is as follows:
- The die b is of the usual form and construction, such as is used in the exterior threading of pipe, by being of circular shape 25 and formed in two halves, both of which when secured together within the openings 4 in the die-head A will allow the passing of the pipe (not shown) through the usual opening formed between such halves for being engaged by the threading means in the die extending into such opening, and such die being held in such head by the usual screw bolts indicated at 30 which pass through such head and die.
- 30 The yokes 1 and 2 are opened by the operator grasping the handle 29 and lever 15, and by pulling the handle outward, and the lever upward, the shoulder 28 on the bar 24 will be released upon and under the extension 3 on the yoke 2 and such bar swing outward, as shown in Fig. 1, while the lever 8 connected to the lever 15 will be thrown to the angle shown in said figure, and short arms on the levers 11 pulled inward by also 40 being connected to said lever 15, so that the front extensions 3 on the head A will be thrown outward. The pipe to be exteriorly threaded can then be placed within the opening formed between the halves of the die b 45 and set at the proper point for threading when the yokes 1 and 2 carrying such die-halves can be brought toward each other by the operator again grasping the lever 15 and handle 29 and by pulling down on said lever 50 will thus move the lever 8 to a horizontal position and the levers 11 outward to allow the long arms on said levers 11 to enter the recessed portions 14 in the front extensions 3. This will cause the front extensions 55 60 to be brought toward each other and thus allow the closing of the die-head A so that the threading of the pipe can be made by the means on the die b engaging with the exterior of the pipe, and when so closed the operator simply moves the locking bar 24 65

inward by the handle 29 in order to allow the shoulder 28 on said bar to fit under the end of the extension 3 on the lower yoke 2 and thereby lock the yokes 1 and 2 in their closed positions.

Various modifications and changes in the design and construction of my improved die-head may be resorted to without departing from the spirit of the invention or sacrificing any of its advantages.

It will thus be seen that in the use of my improved quick-opening and closing die-head, the operations will require less effort on part of the operator than with ordinary forms of die-heads, while less wear will be 80 had on wearing parts and fewer wearing parts will be provided than in the usual constructions.

It will further be seen that by use of the compound lever motion for the opening and closing of the die-head, a quick and easy movement is effected which will readily and conveniently open the head to release the threaded pipe and close the same when the pipe is to be threaded, while the opening of 90 the die-head and unlocking of the same can be made at one operation, and such locking of the head will be rigid and positive and can easily and quickly be made when desired.

What I claim as my invention and desire to secure by Letters Patent is:

1. A die head formed of two yokes movably connected together at one end, lever means positioned entirely between the yokes at the opposite end of the same for opening and closing said yokes, said yokes being recessed for the reception of said lever means when in closed position, and operating means for the lever means at one side 100 thereof.

2. A die-head formed of two yokes and movably connected together at one end, a rocking lever having both ends slotted mounted between the other end of said 110 yokes, and levers pivoted at one end to the slotted ends of said lever and at the opposite end to said yokes for opening and closing said yokes.

3. A die-head formed of two yokes and movably connected together at one end, a rocking lever mounted between the other end of said yokes, L-shaped levers pivoted to said lever and to said yokes, and an operating lever for moving the same and said 120 L-shaped levers in the opening and closing of said yokes.

4. A die-head formed of two yokes movably connected to a common supporting means at one end, means disposed between 125 the yokes for effecting the opening and closing thereof, said yokes being recessed at said end to receive the operating means when in closed position, and independent means for locking the yokes in closed position.

5. A die-head formed of two yokes and
movably connected together at one end,
means for opening and closing said yokes,
and a locking bar movably and adjustably
5 carried by one of said yokes for engaging
with the other yoke to hold said yokes in
position.

6. A die-head formed of two yokes and
movably connected together at one end,
10 means for opening and closing said yokes,

and a locking bar movably and adjustably
carried by one of said yokes and having a
shoulder for engaging with the other yoke to
hold said yokes in position.

In testimony whereof, I, the said WIL- 15
LARD C. MARKS have hereunto set my hand.

WILLARD C. MARKS.
